(57) **CLAIM**

The ornamental design for a tongue depressor, as shown and described.

DESCRIPTION

FIG. 1 is an exploded top view of a tongue depressor, showing our new design;

FIG. 2 is a first side view of the tongue depressor of FIG. 1 in an assembled state, the second side view being a mirror image of the tongue depressor of FIG. 1;

FIG. 3 is an exploded side view of the tongue depressor of FIG. 1;

FIG. 4 is a perspective view of the tongue depressor of FIG. 1 in an assembled state;

FIG. 5 is an exploded perspective view of the tongue depressor of FIG. 1;

FIG. 6 is a top view of the tongue depressor of FIG. 1 in an assembled state;

FIG. 7 is a bottom view of the tongue depressor of FIG. 1 in an assembled state;

FIG. 8 is an exploded bottom view of the tongue depressor of FIG. 1;

(Continued)

FIG. 9 is a first end view of the tongue depressor of FIG. 1;
and,
FIG. 10 is a second end view of the tongue depressor of FIG.
1.

1 Claim, 10 Drawing Sheets
